ROBERT L. BROWN, OF MILWAUKEE, WISCONSIN, ASSIGNOR TO HARNISCHFEGER CORPORATION, OF MILWAUKEE, WISCONSIN, A CORPORATION OF WISCONSIN

TRENCH-DIGGING MACHINE

Application filed June 14, 1926. Serial No. 115,821.

This invention relates to improvements in trench digging machines of the so-called ladder type, and more particularly to an improved construction of trench widening apparatus and supporting and driving means therefor.

Trench digging machines of the class referred to include a boom and a plurality of excavating buckets carried thereby and fixed 10 on endless chains arranged to travel longitudinally around the boom, these chains being driven from a power shaft which also acts to pivotally connect the high end of the boom to the superstructure at the rear end 15 of the machine carrying the power plant and driving mechanism, the latter being generally mounted on endless traction belts. The width of the trench which these machines are capable of digging depends upon the 20 width or reach of the excavating buckets. For the purpose of increasing the possibilities of the machine as regards the width of a trench it is capable of digging, it has been proposed to attach cutting elements to either 25 side of the boom and to reciprocate the same in a direction longitudinally of the boom as the machine moves along, whereby these elements cut away the earth to either side of the excavating buckets and make a correspondingly wider trench, the loose dirt cut 30 away by these elements falling into the path of the excavating buckets and being removed thereby. These cutting elements or trench 35 widening means used heretofore operate with a sawing action to cut away the earth at either side of the boom and are comparatively light in construction, and in no way adapted to dig into the earth with a plowing 40 action as do the excavating buckets.

One of the objects of the present invention is to provide, in a machine of the character referred to, an improved trench widening attachment adapted to be attached to and to 45 be carried by the boom, and one which shall operate to dig into the earth with a plowing action in the same manner as the excavating buckets, the improved attachment having advantages over those constructed heretofore as 50 regards increase in the width of the trench,

general operation, ruggedness and strength and simplicity of construction.

Other objects and advantages will herein-after appear.

For the purpose of illustrating the invention, one embodiment thereof is shown in the drawings, in which

Fig. 1 is a side elevational view of the rear end of a trench digging machine embodying the present improvements;

Fig. 2 is a plan view of Fig. 1;

Fig. 3 is an enlarged sectional view, taken on the line 3—3 in Fig. 2;

Fig. 4 is an enlarged sectional view, taken on the line 4—4 in Fig. 2;

Fig. 5 is a detail fragmentary perspective view;

Fig. 6 is a sectional view, taken on the line 6—6 in Fig. 3;

Fig. 7 is a sectional view, taken on the line 7—7 in Fig. 2;

Fig. 8 is a diagrammatic view showing a modification;

Fig. 9 is a fragmentary plan view showing a modification; and

Fig. 10 is an enlarged, fragmentary view taken from Fig. 2.

The boom 10, which may be of any suitable construction, is provided at its upper or high end with spaced collars 11 fitting loosely on the drive shaft 12 journaled in suitable manner in the superstructure or framework 13 at the rear end of the machine, which is supported at either side on endless traction belts 14. For the purpose of driving shaft 12, a sprocket wheel 15 is fixed on one end thereof and connected in suitable manner to the power mechanism (not shown), mounted on the base 16 of the machine.

Sprocket chains 17 and 18, to which the excavating buckets 19 are fixed, are arranged to travel about the sheaves 20 carried by the lower end of the boom and the sprocket wheels 21 fixed on shaft 12 and which act to drive these chains. The upper run of the chains is supported and guided on pulleys 22 fixed on the ends of shafts 23 rotatably supported by the boom.

A shaft 24 extends transversely through the boom intermediate the ends thereof and is

journalized in suitable bearings 25 secured to the boom on either side of the same, as more clearly shown in Figs. 2 and 3, the ends of shaft 24 extending beyond each side of the boom. Cranks 26 are fixed on the extended ends of shaft 24 and are provided at their free ends with fixed pins 27 extending outwardly beyond and at right angles to the boom. A similar shaft 28 extends through the lower end of the boom and is journalized in bearings 29 fixed on either side thereof, and being similar in construction to bearings 25, cranks 30 being fixed on the ends of this shaft and provided at their free ends with fixed pins 31 which also extend outwardly beyond and at right angles to the boom.

The improved trench widening attachment includes digging members, designated generally in Fig. 2 by reference numerals 32 and 33, arranged upon either side of the boom and extending longitudinally thereof. Member 32 comprises a bearing 34 fitted loosely on the pin 27, a similar bearing 35 fitted loosely on pin 31, and spaced parallel bars 36 connected at their ends to the respective adjacent laterally extending portions 34' and 35' of bearings 34 and 35 respectively, a plurality of U-shaped brackets 37 depending from bars 36, as more clearly shown in Fig. 3, and being secured at their upper ends to these bars, digging teeth 38 being fixed to the lower portions 39 of these brackets by means of rivets or bolts 40, as more clearly shown in Fig. 6. The teeth 38 extend downwardly and operate to plow into and dig away the earth at either side of the excavating buckets 19. For the purpose of finishing the side of the trench, digging members 41 are secured to the outer bar 36 by means of the same bolts 42 by which the ends of brackets 37 are secured to this bar, as more clearly shown in Fig. 5. Each of the digging members 41 comprises the shank 43 and a forwardly and downwardly extending blade 44, the plane of the blade being angularly disposed with respect to the plane of shank 43 and the plane of movement of the blade, whereby the latter during its working stroke to the left, as viewed in Figs. 1 and 2, operates to cut away and finish the side of the trench and to direct the cut material inwardly toward the center of the trench into the path of movement of the excavating buckets by which this material is then removed.

Another U-shaped bracket 37 also provided with teeth 38 and a side digging member 41 may be secured to the outer laterally extending portion 45 of bearing 34, as shown. A similar U-shaped bracket 37' provided with teeth 46 fixed to the portion 47 thereof and a digging member 48 similar in construction to the digging members 41, is fixed as shown to the outer laterally extending portion 49 of bearing 35. As indicated in Figs. 2 and 3 the portions 39 and 47 of the U-shaped brackets 37 and 37', respectively, are inclined down-

wardly and inwardly so that the loose earth will be moved into the path of movement of buckets 19.

The digging member 33 is similar in construction to member 32, the ends of this member being provided with the bearings 50 and 51 fitted loosely, respectively, on crank pins 27 and 31.

Shaft 24 is driven by means of a sprocket wheel 52 fixed thereto and arranged centrally of the boom. A sprocket chain 53 provides a driving connection between sprocket wheel 52 and a similar sprocket wheel 54 fixed to drive shaft 12.

For the purpose of holding the upper run 80 of chain 53 out of the way of buckets 19, an idler pulley 55 engages the upper side of this portion of the sprocket chain between pulleys 22, pulley 55 being loosely mounted on a pin 56 fixed in the outer ends of links 57 loosely 85 mounted at their other respective ends on upper shaft 23, as more clearly shown in Fig. 2. Straps 58 are fixed to the outer ends of links 57 and are provided with threaded stems 59 extending downwardly through suitable 90 brackets 60 fixed on each side of the boom, nuts 61 being threaded on stems 59 and engaging the undersides of brackets 60 to limit upward movement of pulley 55.

As more clearly shown in Fig. 3, the boom 95 10 may comprise vertically spaced channel members 61 connected by side plates 62, and angle members 63 extending longitudinally of the boom and being secured to the upper and lower edges of plates 62, the plates 62 100 and angle members 63 forming, in effect, horizontally spaced channel members to which the bearings 25 and 29 are secured, the bearings 25 being spaced and channel members 61 being provided with openings 64 to accommodate sprocket wheel 52.

The operation of the improved trench widening apparatus is as follows: Upon rotation of drive shaft 12 in a clockwise direction, as viewed in Fig. 1, shaft 24 will be caused 110 to rotate in this direction and the cranks 26 fixed upon the ends of the latter will in turn cause the adjacent ends of members 32 and 33 to rotate in the path of a circle having the axis of shaft 24 as a center and a radius 115 equal to the length of cranks 26, the lower or outer ends of members 32 and 33 being caused to rotate in the path of a circle having as a center the axis of shaft 28 and a radius equal to the length of cranks 30. For 120 each revolution of shaft 24, therefore, the teeth 38 and the digging members 41, as well as teeth 46 and digging members 48, will be given a forward movement to the left, as viewed in Figs. 1 and 2, teeth 38 and 46 digging into the earth with a plowing action and cooperating with excavating buckets 19, which are also operating at this time, to cut out a trench equal in width to substantially 125 the combined reach of buckets 19 and these 130

teeth, the side digging members 41 and 48 cutting away and finishing the side of the trench and directing the cut material inwardly toward the center of the trench and into the path of movement of buckets 19.

As shown in Fig. 8, the lower cranks 30', corresponding to cranks 30 in Fig. 2, may be made greater in length than cranks 26, whereby the lower or outer ends of members 32 and 33 will merely be given a rocking or oscillatory movement about the axis of shaft 28 upon rotation of the upper ends of these members about the axis of shaft 24. It will be understood, furthermore, that the width 15 of the trench cut may be increased by making shafts 24 and 28 longer to cause their respective ends and the attached members 32 and 33 to extend a greater distance outwardly beyond the sides of the boom, and that 20 one or both sides of the trench may be cut on a slope by removing one or the other or both of the pins 27 in Figs. 1 to 4 and substituting therefor a longer pin 27', as shown in Fig. 9, whereby one or both of the members 32 and 33 will be disposed at an angle 25 with respect to the boom.

To provide against the possibility of the cranks on both sides of the boom being in dead center position at the same time, in 30 the construction where cranks 30 are made equal in length to cranks 26, the cranks on one side of the boom may be offset about fifteen degrees with respect to the cranks on the other side of the boom, as more clearly 35 shown in Figs. 3 and 7. While this amount of offset, namely fifteen degrees, has been found to provide for satisfactory operation, it will of course be apparent that this amount of offset may be made greater or less as desired.

Either one or both of the trench widening members 32 and 33 may be readily removed by removing the cranks 26 and 30 from the respective ends of shafts 24 and 28 at either 45 or both ends of the boom.

One embodiment of the invention has been shown and described, but of course various changes may be made such as in the size, shape and arrangement of the parts without departing from the spirit of the invention 50 or the scope of the claims.

The invention claimed is:

1. In a trench digging machine of the character described, the combination with the boom and excavating buckets carried thereby, and the power shaft for pivotally supporting the high end of said boom and driving said buckets, of a second shaft journaled in said boom intermediate the ends thereof, 55 digging means including a member arranged to one side of said boom and extending longitudinally thereof, one end of said member being connected to said second shaft for rotation therewith about the axis thereof, the other end of said member being supported by

the free end of said boom for rotary movement about an axis parallel to the axis of said second shaft, and means for rotating said second shaft.

2. In a trench digging machine including a boom, a pair of spaced shafts carried by said boom at the digging end thereof and arranged transversely of the same, a digging member arranged to one side of said boom and extending longitudinally thereof, the respective ends of said shafts at said side of the boom being provided with cranks, one of said cranks being fixed to its associated shaft, the ends of said member being pivotally connected to the respective free ends of said cranks, and means for rotating said last-named cranks whereby the end of said member connected thereto is caused to rotate in the path of a circle having the axis of said shaft as a center and a radius equal to the length of the fixed crank.

3. In a trench digging machine having a boom, an element carried by said boom and supported thereby for forward and backward movement with respect to the latter in a direction longitudinally of the same, a digging member comprising a shank secured to said element and a downwardly extending blade, the plane of said blade being angularly disposed with respect to the plane of said shank in such wise as to direct the cut material toward the center of the trench during the working stroke of the digging member, and operating means for said element.

4. In a trench digging machine of the character described including a boom and excavating buckets carried thereby, a member arranged to one side of said boom and supported thereby for relative forward and backward movement in a direction longitudinally thereof, digging elements secured to the under side of said member and arranged for cooperation with said buckets to cut out a trench equal in width to substantially the combined reach of the buckets and digging elements, means secured to said member and extending outwardly beyond the same to finish the adjacent side of the trench, and means for driving said member.

5. In a trench digging machine of the character described including a boom and excavating buckets carried thereby, a member arranged to one side of said boom and supported thereby for relative forward and backward movement in a direction longitudinally thereof, digging elements secured to the under side of said member and arranged for cooperation with said buckets to cut out a trench equal in width to substantially the combined reach of the buckets and digging elements, a plurality of downwardly extending aligned blades secured to said member and extending outwardly beyond the same to finish the adjacent side of the trench, said blades being angularly disposed with respect to their plane

of movement whereby the latter are operable during their working stroke to cut and direct the cut material toward the center of the trench, and means for driving said member.

5 6. In a trench digging machine of the character described including a boom and excavating apparatus carried thereby, a member arranged to one side of said boom and extending longitudinally thereof, a plurality of sets of digging elements spaced longitudinally of said member and secured thereto, the elements of each set extending downwardly below said member, a pair of spaced shafts carried by the digging end of said boom and 10 arranged transversely thereof, cranks carried by the respective ends of said shafts at said side of the boom, said member being pivotally connected at its ends to the free ends of said cranks, one of said cranks being fixed 15 with respect to its associated shaft, and means for driving said last-named shaft.

20 7. In a trench digging machine of the character described including a boom, a pair of spaced shafts journaled in said boom at the digging end thereof and extending transversely of the latter with their respective ends extending beyond the same, cranks carried by said shafts at their extended ends, digging members arranged on either side of said boom 25 with their ends pivotally mounted on the free ends of said cranks, the cranks carried by one of said shafts being fixed thereto, and means for rotating said last-named shaft.

25 8. In a trench digging machine of the character described including a boom, a pair of cranks pivotally mounted on said boom at the digging end thereof, crank pins extending from the respective ends of said cranks outwardly beyond one side of said boom at right 30 angles with respect thereto, bearings loosely mounted on said pins, said bearings being provided with laterally and inwardly extending portions, means connecting said bearing portions, digging members secured to said 35 connecting means at spaced intervals along the latter and extending downwardly below the same, and means for imparting rotary movement to one of said cranks.

40 9. In a trench digging machine of the character described including a boom, a pair of cranks pivotally mounted on said boom at the digging end thereof, crank pins extending from the respective ends of said cranks outwardly beyond one side of said boom at right 45 angles with respect thereto, bearings loosely mounted on said pins, said bearings being provided with laterally and inwardly extending portions, means connecting said bearing portions, digging members secured to said 50 connecting means at spaced intervals along the latter and extending downwardly below the same, and means for imparting rotary movement to one of said cranks, certain of 55 said members comprising each a shank fixed 60 to said connecting means and a cutting blade 65

extending outwardly beyond the outer edge of said connecting means and being disposed at an angle with respect to the plane of movement of the latter.

70 10. In a trench digging machine of the character described including a boom, a pair of spaced shafts extending transversely through the digging end of said boom and journaled therein, cranks fixed on the respective ends of said shafts, digging members arranged on either side of said boom and extending longitudinally thereof, the ends of said members being pivotally connected to the respective ends of said cranks, the cranks on one side of said boom being angularly offset with respect to those on the opposite side of said boom, and means for imparting rotary movement to one of said shafts.

75 11. In a trench digging machine of the character described including a boom, a pair of cranks pivotally mounted on said boom at the digging end thereof, crank pins extending from the respective ends of said cranks outwardly beyond one side of said boom at right angles with respect thereto, bearings loosely 80 mounted on said pins, said bearings being provided with laterally and inwardly extending portions, spaced parallel bars connected at their respective ends to said bearing portions, a plurality of depending brackets secured to said bars and spaced longitudinally of the same, said brackets being provided with digging members, and means for imparting 85 rotary movement to one of said shafts.

90 12. In a trench digging machine of the character described including a boom, a pair of cranks pivotally mounted on said boom at the digging end thereof, crank pins extending from the respective ends of said cranks outwardly beyond one side of said boom at right angles with respect thereto, bearings loosely 95 mounted on said pins, said bearings being provided with laterally and inwardly extending portions, spaced parallel bars connected at their respective ends to said bearing portions, a plurality of depending U-shaped 100 brackets secured at their ends to said bars and spaced longitudinally of the same, said brackets being provided with digging members, and means for imparting rotary movement to one of said shafts.

105 13. In a trench digging machine of the character described including a boom, a crank carried by said boom and provided at its free end with a pin, a bearing mounted on said pin and provided with a laterally extending portion, a bracket fixed to said bearing portion, a digging element secured to said bracket and depending therefrom, and means for imparting movement to said 110 crank.

120 14. In a trench digging machine of the character described, a boom, a pair of crank shafts carried by said boom at the digging end thereof, cranks fixed on said shafts at 125

each side of said boom, the cranks on one side of said boom being angularly offset with respect to the cranks on the other side of said boom, digging members arranged on either side of said boom and pivotally connected at 5 their ends to the respective free ends of said cranks, and means for imparting rotary movement to one of said shafts.

15. In a trench digging machine of the character described including a boom, a crank carried by said boom and provided at its free end with a pin, a bearing mounted on said pin and provided with a laterally extending portion, a U-shaped bracket fixed at 10 its ends to said bearing portion, digging elements secured to said bracket and depending therefrom, and means for imparting movement to said crank.

20. In a trench digging machine of the character described, a boom, a U-shaped bracket arranged transversely of said boom and carried thereby for oscillatory movement in a direction longitudinally of the same, said bracket having a portion downwardly and inwardly disposed with respect to the longitudinal axis of said boom, a digging element carried by said bracket portion, and means for imparting said movement to 25 said bracket.

30. 17. In a trench digging machine of the character described, the combination with a boom and excavating buckets carried thereby, of digging means arranged along one side of the boom, and including a digger mounting member extending longitudinally of the boom to one side thereof, digger elements carried on said digger mounting member and means imparting translatory movement to the digger mounting member in an endless 35 path whereby the digger elements operate to excavate the earth with a plowing action.

40. 18. A trench widening apparatus for use on a trench digging machine having the usual boom and excavating buckets and comprising a rotatable shaft supported intermediate the boom, digging means extending along the sides of the boom, mechanism between the shaft and the digging means for imparting bodily movement to the digging means in an 45 endless path when the shaft is rotated and gearing directly connected to the shaft for rotating the same.

50. 19. In a trench digging machine of the character described, the combination with a boom and excavating buckets carried thereby, of digging means arranged along one side of the boom, cranks supported upon the boom and projecting laterally therefrom and connected with the digging means for imparting 55 translatory movement thereto in an endless path, and means for driving said cranks.

59. 20. In a trench digging machine, the combination with a boom and excavating buckets carried thereby, of digging means arranged 65 along one side of the boom, means for sup-

porting the digging means upon the boom and driving means for imparting movement in an endless path to one end of the digging means whereby the digging means is operable to excavate earth with a plowing action.

70. In witness whereof, I hereto affix my signature.
